United States Patent Office

Des. 183,440
Patented Aug. 26, 1958

183,440

ARMCHAIR

Herbert E. Williams, Temple, Tex.

Application May 14, 1957, Serial No. 46,172

Term of patent 14 years

(Cl. D15—1)

FIG. 1.

FIG. 2.

Figure 1 is a perspective view of an armchair embodying my new design;

Figure 2 is a top plan view thereof;

Figure 3 is a rear elevational view thereof;

Figure 4 is a side elevational view thereof; and

Figure 5 is a bottom plan view thereof.

The dominant features of the design are shown in full lines.

I claim:

The ornamental design for an armchair, substantially as shown and described.
